WITNESS:

P. F. Beck

INVENTOR,
BY *Franz A. Boedtcher*
James H. Griffin
ATTORNEY

UNITED STATES PATENT OFFICE.

FRANZ A. BOEDTCHER, OF BERGENFIELD, NEW JERSEY.

EMERGENCY-SWITCH PROTECTOR.

1,367,854.

Specification of Letters Patent.

Patented Feb. 8, 1921.

Application filed August 21, 1918. Serial No. 250,775.

To all whom it may concern:

Be it known that I, FRANZ A. BOEDTCHER, a citizen of the United States, residing in Bergenfield, county of Bergen, and State of New Jersey, have invented a certain new and useful Emergency-Switch Protector, of which the following is a specification.

This invention is an emergency switch protector, and, speaking generally, the object of the invention is to preclude such a switch from being tampered or interfered with until it becomes necessary to use the switch for its intended purposes, whereupon it is necessary to break or disrupt some temporary protecting element, such as a glass plate, forming one of the elements of the switch mechanism casing or housing.

As is well known, it is customary to install in elevators, an emergency switch, controlling the operating circuit; *e. g.*, the circuit in which the magnet switches are located. It is common practice to inclose such switch mechanism and operating push buttons in a casing provided with a glass panel, the aim being to protect the mechanism against mischievous or inadvertant operation by passengers, or others, to the extent afforded by the glass panel, since the push buttons are not accessible for operation until after the glass panel has been broken.

In the protective casings described, however, the frames containing the glass panels, being usually screwed in position or otherwise detachably secured, can be readily removed and replaced without breaking the panels, and, accordingly, comparatively little protection is afforded by such casings.

The present invention obviates the disadvantage referred to, and others, in that it embodies a protective casing of the general type specified, but one wherein the push buttons are absolutely inaccessible until after the glass panel has been broken, thereby precluding any tampering with the switch mechanism under normal working conditions.

In the accompanying drawings, I have illustrated one practical, and the preferred, embodiment of the invention, but the construction shown therein is illustrative only, and not exclusive of the different forms in which the invention may be embodied.

Referring to the drawings, Figure 1 is a perspective view of the exterior of the casing, certain parts of the interior structure being shown in dotted lines;

Fig. 2 is a transverse section on line 2-2 of Fig. 1, looking in the direction of the arrow appearing on said line; and

Fig. 3 is a cross section on line 3-3 of 60 Fig. 2.

Referring to the drawings, 5 is the switch housing, usually composed of sheet metal, provided at its front with a glass panel 6. Interiorly of the casing is the customary 65 switch mechanism which need not be described with particularity as it forms, *per se*, no part of the present invention. Suffice it to refer to the supporting frame 7, having open sides, and top and bottom 8 and 9, 70 respectively, bent in U-shaped form, as shown in Fig. 2. Frame 7, through the medium of an upright member 10, secured to porcelain insulating casing 11, which incases the switch mechanism, and the screws 12 and 75 13 which take into the top and bottom portions, respectively, of frame 7, serves to support said porcelain insulating casing 11. The customary push buttons are designated 14, and they project through the face plate 80 15, which is secured to upright member 10 by screws 16.

From a structural standpoint, the essence of the present invention, in the embodiment shown, consists in providing on the inner 85 side walls of housing 5, leaf springs 17, affixed to the casing at one end as at 18, leaving the other ends 19 free. These free ends project inwardly as shown in Fig. 3, and stamped up therefrom are the inwardly extending ears 20.

The supporting frame 7, and associated switch mechanism can be handled as a unit, and the frame is secured to the inner wall of the car, in any convenient location by screws 95 or otherwise. When the casing 5 is inserted in place over frame 7 and associated parts, the ends 19 and lugs 20 of springs 17 are forced apart, thereby permitting plate 15 to assume a position rearwardly of the lugs, 100 whereupon the lugs, owing to the ends of the springs moving inwardly, are carried behind plate 15, whereby, the casing is locked in position, see Fig. 3.

As a result of the construction described, 105 the switch mechanism cannot be operated without breaking the glass panel, and, moreover, if the glass panel is inadvertently or intentionally broken, it cannot be replaced without removing the casing from the housing and this can only be done after the ends of the leaf springs have been spread apart 110

sufficiently to permit the lateral edges of the face plate 15 to pass the lugs 20.

It will be understood that slight changes may be made in the structure described, such as the substitution of equivalents, without departing from the spirit or substance of the invention, the scope of which is commensurate with the appended claims.

Having thus described the invention, what I claim as new, and desire to secure by Letters Patent, is:

1. A device of the class described embodying a frame-work adapted to be secured to a fixed support, switch mechanism mounted on the frame-work, a casing provided with an open back and having a front opening provided with a transparent closure inserted from the back of the casing and removable only through said back except by breakage of the closure, and spring fingers mounted on the interior of the casing and adapted to engage with the frame-work when the casing is brought into a position to inclose said frame-work for the purpose of automatically locking the casing in position, whereby it can only be removed or the switch mechanism operated by first breaking the transparent closure.

2. In a device of the class described, switch mechanism embodying a rigid frame-work supporting electric circuit controlling mechanism and adapted to be, in turn, mounted on a fixed support, a casing provided with an open back and a transparent closure at the front thereof, said transparent closure being removable through the front opening only through breakage of the closure, and resilient catches mounted on the casing and adapted to automatically engage with the rigid frame-work of the switch mechanism when the casing is brought into a position to house the switch mechanism with the open back of the casing against the fixed support, whereby the removal of the casing or the

operation of the circuit closing mechanism is precluded until the closure is broken.

3. In a device of the class described, switch mechanism embodying a frame-work supporting electric circuit controlling means, a casing open at its back and front and provided at its front with flanges formed by bending in the walls of the casing, a transparent closure inserted into the casing from the back thereof to rest against the inner faces of said flanges, and of such size as to be removable from the casing only through the back opening except by breakage of the closure, and resilient means positioned on the interior of the casing and adapted to automatically engage the same when the casing is brought into a position to house the switch mechanism for the purpose of locking the casing against removal, and to preclude the operation of the circuit controlling means until the transparent closure is broken.

4. A device of the class described embodying switch mechanism adapted to be mounted on a fixed support, a casing provided with an open back and having a front opening of lesser area than the cross sectional area of the casing, a transparent closure of greater size than the front opening positioned within said casing and covering the front opening, whereby said closure can only be removed through the front opening by breaking the closure and resilient means associated with the switch mechanism and with the interior of the closure for automatically locking the closure in a position to house the casing with the open back of the casing against the fixed support, for the purpose of precluding removal of the casing or the operation of the switch mechanism until the transparent closure is broken.

In testimony whereof, I have signed my name to this specification.

FRANZ A. BOEDTCHER.
